DESIGN.

M. HERSKOVITZ.

LIGHTING FIXTURE.

APPLICATION FILED APR. 1, 1915.

48,492.

Patented Feb. 1, 1916.

Inventor:

Max Herskovitz,
by Charles O. Shervey, his Attorney.

UNITED STATES PATENT OFFICE.

MAX HERSKOVITZ, OF CHICAGO, ILLINOIS.

DESIGN FOR A LIGHTING-FIXTURE.

48,492.

Specification for Design.

Patented Feb. 1, 1916.

Application filed April 1, 1915. Serial No. 18,620. Term of patent 3½ years.

To all whom it may concern:

Be it known that I, MAX HERSKOVITZ, a citizen of the United States, residing at Chicago, in the county of Cook and State of Illinois, have invented a new, original, and ornamental Design for a Lighting-Fixture, of which the following is the specification, reference being had to the accompanying drawing, forming part thereof.

In said drawing, the figure is a perspective view of a lighting fixture showing my design.

I claim:

The ornamental design for a lighting fixture, as shown.

MAX HERSKOVITZ.
